UNITED STATES PATENT OFFICE.

CHARLES A. VAN ALLEN, OF CHICAGO, ILLINOIS, ASSIGNOR TO ROBERT K. SCOTT, OF NAPOLEON, OHIO.

SPRING FOR KEEPING PITMEN OFF DEAD-CENTERS.

SPECIFICATION forming part of Letters Patent No. 254,248, dated February 28, 1882.

Application filed June 13, 1881. (No model.)

To all whom it may concern:

Be it known that I, CHARLES A. VAN ALLEN, a citizen of the United States, residing at Chicago, county of Cook, and State of Illinois, have invented a certain new and useful 5 Spring for Keeping the Pitmen of Sewing-Machines Off of the Dead-Centers, of which the following is a specification.

My invention relates to an improvement in 10 springs, and in the manner of attaching such springs to and operating them upon the pitman of a sewing-machine, so as to keep the pitman off of both its upper and lower center.

The object of my invention is to avoid the 15 necessity of starting by hand the belt or fly wheel to set the machine in motion; to have the machine run with a continuous uniform motion—that is, without being subject to sudden or violent jerks; and, finally, to enable the 20 operation of the treadle by a toe-pressure alone, and by the exertion of less power and with greater ease than those now in common use. I attain these objects by a device illustrated in the accompanying drawings, in 25 which—

Figure 1 is a side elevation of my spring attached, and showing its position when the pitman is on the upper dead-center; and Fig. 2, a similar view with the pitman on the lower 30 dead-center.

Similar letters of reference indicate the same parts in the figures of the drawings.

A represents the lower and larger coil of a wire spring removably clamped to a treadle 35 of a sewing-machine intermediate the pivot of the treadle and the pivot of the pitman by ordinary clamping-plates and a thumb-screw, a projecting end of the coil being rigidly secured to the upper plate. Contiguous 40 with the spring A is an arm, a, extending beyond the pitman and at an oblique angle to a horizontal plane, and having an eye, a', formed at its center of length by bending the wire. From the upper end of the arm a is a coiled spring, B, similar but smaller, and having 45 its coils wound opposite to those of the spring A—that is to say, the arm passes from the bottom of the spring A to the top of spring B, as clearly shown in the drawings, so that 50 the coils of the springs are necessarily wound

in opposite directions relative to each other. The outer coil of spring B terminates in an oblique arm, b, which, crossing the arm a, terminates in an eye, c, by means of which it is pivotally secured upon a lug or button upon 55 the clamping-plate, securing said arm to the pitman, or by a lug upon the pitman.

As at present constructed the spring A consists of three coils, while the spring B consists of two coils; but the number of coils or the 60 relative size of them is surely optional and dependent upon the resistance of the crank and the size of wire used, and also the length of the arms a b, which, while operating as levers, have to a limited extent the function of 65 springs.

To prevent the lower coil from contracting or overcoming the action of the upper coil during a certain portion of the stroke of the pitman, as will be presently described, hook-arm 70 D, rigidly fixed upon the clamping plate, or else to the treadle, is connected by an adjustable chain, E, or other suitable device, to the eye a' upon the arm a.

In Fig. 1 the dotted line 1 3 indicates the 75 line of the dead-centers, while the dotted line 2 4 indicates opposite points exactly between the dead-centers.

To attach the spring the crank-arm is turned until on the line 2 4, (at which moment the 80 springs and arms, if already attached, would be in their normal condition,) and having clamped the spring A to the treadle, making its pivot and the pivot of the crank, the arms a b are slightly spread, so that the spring may 85 not be loose, and arm b is then clamped to the pitman.

It will be observed that the pitman is never 90 vertical, but nearest it when the upper pivot is at 2, and farthest off when at 4; that when 95 at either of these points the arms a b, and consequently the springs A B, are in their normal condition; and that the dead-centers of the pitman are at one side or the other, as the case may be, of a vertical line, 5 6, drawn through the axis of the belt or balance wheel. Furthermore, that when the upper pivot of the pitman is at 5 the arms a b are spread apart, the spring A expanded, and the spring B contracted to their utmost limits, and vice versa 100

when the upper pivot of the pitman is at 6. Supposing the upper pivot of the pitman to be at 4, it will be understood that if a toe-pressure be exerted upon the treadle the pitman will descend and the arms of the springs be caused to approach each other until the upper pivot of the pitman is at 6, when they begin to recede from each other.

Owing to the fact that the arm *b* is shorter, 10 and consequently more rigid, this movement has the effect of uncoiling and consequently expanding the spring *B*, and of lifting the arms *a b*, and hence contracting the spring *A*.

As soon as the pivot of the pitman passes the 15 vertical line 5 6 toward its lower dead-centers, and the arms commence spreading apart, these springs exert themselves to resume their normal condition, and in doing so carry the pitman beyond the lower dead-center.

20 Under an ordinary toe-pressure, when starting the machine, the momentum of the balance-wheel is not sufficient to overcome the resistance of both springs, so as to carry the pivot of the pitman upwardly beyond the vertical line 5 6, though the toe-pressure is augmented by the contraction and expansion of the springs as soon as the pivot of the pitman passes the line 5 6. To obviate this difficulty the chain *E* is used, which has the effect of holding up the arm *a* and preventing the spring *A* from expanding during the time in which the pivot of the pitman is traveling from 2 to 4, the expansion of the contracted spring *B*, after passing the line 5 6, being alone 35 sufficient to throw the pitman off its dead-centers, when the toe-pressure may be again utilized.

Instead of a chain which admits of adjustability connecting the spring *A* with the eye

a' in the arm *a*, a hinged rod may be used, 40 and in some instances both may be dispensed with and a lug be placed under to support the arm *a*, to prevent it from descending and the coil *A* from expanding.

Having thus described my invention, what I 45 claim, and desire to secure by Letters Patent, is—

1. The combination, with a pitman and with its operating treadle, of a spring connected with said pitman and treadle, and adapted to 50 throw the pitman off its dead-centers, substantially as described.

2. The combination, with a pitman and treadle, of an actuating-spring consisting of two or more coils, and adapted to simultaneously contract and expand, for the purpose set forth.

3. The combination, with a pitman and treadle, of a spring having two or more coils simultaneously expanding and contracting, 60 and a tension chain or cord connected with and adapted to limit the expansion of one of said springs.

4. In a sewing-machine, the combination, 65 with the pitman and treadle, of a spring consisting of the coils *A B*, an arm, *a*, connecting said coils, and an arm, *b*, connecting the coil *B* with the pitman.

5. The combination, with the coils *A B* and arms *a b*, connecting said coils with each other 70 and with the pitman and treadle, of an arm, *D*, and a tension chain or cord connecting the arm *a* with the arm *D*, substantially as and for the purpose set forth.

CHARLES A. VAN ALLEN.
